COMBINED CONDIMENTS SHAKER SET AND TRAY THEREFOR

Augusto Salviato, Corso Mario Abbiate 110,
Vercelli, Italy

Filed June 11, 1973, Ser. No. 368,891

Term of patent 14 years

Int. Cl. D7—06

U.S. Cl. D7—55

Fig. 1

Fig. 2

FIG. 3

FIG. 1 is a side elevational view of a combined condiment shaker set and tray therefor showing my new design; FIG. 2 is a top plan view thereof; FIG. 3 is a bottom plan view thereof; and FIG. 4 is an end view thereof.

I claim:

The ornamental design for a combined condiment shaker set and tray therefor, as shown.
